UNITED STATES PATENT OFFICE.

LEVI DEDERICK, OF NEW YORK, N. Y.

IMPROVEMENT IN PITMEN.

Specification forming part of Letters Patent No. 147,109, dated February 3, 1874; application filed December 31, 1873.

To all whom it may concern:

Be it known that I, LEVI DEDERICK, of the city, county, and State of New York, have invented certain new and useful Improvements in Self-Tightening Journal-Boxes, of which the following is a specification:

This invention relates to that class of journal-boxes used on steam-engines, sawing and mowing machines, &c., for connecting the pitman or connecting rod with the crank-pin, and has for its object to keep the box uniformly tight-fitting by maintaining an equable pressure on the journal to prevent the vibration or thumping incident to loose boxes, and to prevent their becoming loose by wear; and it consists in constructing the box as a hollow or skeleton frame, or case, one end of which forms the fixed half of the box, the skeleton being strengthened by a cross partition or web; in the arrangement within said hollow frame of a spring and wedge; in combination with the movable half of the box, said spring acting on the wedge to hold it in position; in a lip formed on the movable half of the journal-box for preventing the displacement of the wedge; in the corresponding construction of the wedge; in the manner of connecting the spring and wedge together; and in the general combination and arrangement of the co-operating parts of the device.

My improved journal-box is more especially intended for connecting-rods, to receive the crank-pin, and is specially adapted for machinery where a rapid reciprocating motion is used, such as in harvesters, steam-engines, &c., but may also be used for stationary journals.

Figure 1 of the accompanying drawings is a front elevation of the improved journal-box, shown connected with the crank-pin, which appears in section, and showing a portion of the pitman. Fig. 2 is a longitudinal section on line $x x$ of Fig. 1, the crank-pin or journal being removed. Fig. 3 is a perspective view of the movable half of the journal-box removed, showing the arrangement of the overlapping-lip; and Fig. 4 is a like view of the wedge.

As shown in the drawing, A is the hollow or partially-open case, at the end of which is formed the fixed half $e e$ of the journal-box

A C, and the other end secured to the pitman B. An inclined partition or web, b, is formed across the case at any convenient point, or it may be formed by brackets on either side to form shoulders for the wedge D, and in the space between this and the fixed half $e e$ of the journal-box, the wedge D, and the movable half C of the box, are inserted. The spring E is secured within the hollow case at the end opposite the box by a screw or rivet, f, as shown in Figs. 1 and 2, where it is secure from blows or other injuries, and its opposite end passes through an opening provided in the partition b, and enters a slot, g, Figs. 2 and 4, in the wedge, or it may rest on a projection of the wedge. The latter is so arranged that its inclined side is in contact with the correspondingly-inclined partition b, and its straight side in contact with the straight side of the block C, as seen in Fig. 2, or it may be the reverse. The spring exerts a constant pressure on the wedge, to force it endwise between the shoulder b and block C, and keeps the latter always in close contact with the crank-pin or journal h, and adjusts it thereto as fast as the parts become worn, so that the box preserves a proper and uniform tightness, and obviates thumping and heating and all lost motion. Upon the block C is formed a projecting lip, i, Figs. 2 and 3, which overlaps the wedge on its thick side and prevents the retraction or removal of the wedge from the case in one direction, or of the block e in the other. To remove the box from the crank-pin the spring E is pressed back, which raises the wedge and relieves the block C, and the whole may then be withdrawn from the crank-pin.

The advantages obtained by my invention are simplicity of construction, durability, and economy of manufacture, as all the parts are of such a form that they may be readily cast and fitted up with but very little preparation; and the spring being secured within the case it is protected from injury, and, at the same time, is readily accessible; and all the parts may be very readily connected or disconnected, when desired, while the form and construction of the box-frame combine strength with lightness, especially adapting it for use on all machines employing cranks.

What I claim as my invention, and desire to secure by Letters Patent, is as follows:

1. The hollow case A, having an angular partition, in combination with the loose box C and wedge D, substantially as described.

2. The combination of the hollow case A, spring E, and wedge D, substantially as and for the purpose set forth.

3. The block C, having an overlapping lip,

I, in combination with the wedge D, substantially as described.

In witness whereof I have hereunto signed my name in the presence of two subscribing witnesses.

LEVI DEDERICK.

Witnesses:

CHARLES M. HIGGINS,

ARTHUR C. FRASER.
